LIGHTING FIXTURE

Bert C. Pretzer, St. Clair Shores, Mich.

Application March 4, 1952, Serial No. 18,768

Term of patent 14 years

(Cl. D48—23)

To all whom it may concern:

Be it known that I, Bert C. Pretzer, a citizen of the United States, residing at St. Clair Shores, in the county of Macomb and State of Michigan, have invented a new, original, and ornamental Design for a Lighting Fixture, for which the following is a specification, reference being had to the accompanying drawing, in which:

I claim:

The ornamental design for a lighting fixture, substantially as shown.

BERT C. PRETZER.
